UNITED STATES PATENT OFFICE.

JAMES D. GIBBS, OF LOUISVILLE, KENTUCKY, ASSIGNOR TO GIBBS-INMAN COMPANY, OF LOUISVILLE, KENTUCKY, A CORPORATION OF KENTUCKY.

RAILWAY-PASSAGE TICKET.

1,100,724.

Specification of Letters Patent. Patented June 23, 1914.

Application filed November 27, 1911. Serial No. 662,751.

To all whom it may concern:

Be it known that I, JAMES D. GIBBS, a citizen of the United States, residing at Louisville, in the county of Jefferson and State of Kentucky, have invented new and useful Improvements in Railway-Passage Tickets, of which the following is a specification.

My invention relates to the class of tickets

known as exchange tickets, by which is meant tickets which are not sold directly for a certain rate or money consideration, but which are given in exchange for the coupons or detachment from a mileage or scrip ticket previously sold at a reduced rate, and the object of my ticket is to facilitate the work of the ticket agent and minimize the time required to issue it.

Heretofore it has been the practice of ticket agents to insert in both the passage coupon and stub of a book ticket, with pen and ink or indelible pencil, the name of the stations from and to which the ticket is to be used, the number of the mileage or scrip ticket from which the coupons have been taken in exchange, the name of the railway issuing said mileage or scrip ticket, and frequently the date limit of the exchange ticket, after which it is detached from the book and stamped by agent on back of both the passage coupon and the stub. This process is not only burdensome to the ticket agent but very annoying to the traveling public, causing many travelers to miss their trains and bringing forth much criticism.

It is the object of my ticket to obviate much of this difficulty, to accomplish which I print the two parts of the ticket substantially in duplicate, but on opposing sides of the paper so that when folded, the blank spaces of the passage portion, including a fixed space for agent's stamp, exactly register or correspond as to location with the identical spaces on the stub portion, whereby, through the application of a carbon-coated surface on the back of the passage portion of the ticket, all pen or pencil impressions thereon are transferred to the stub portion leaving an exact duplicate of all marks made upon the passage ticket.

With reference to accompanying drawing: Figure 1 represents my ticket, un-

folded, showing the carbonized surface, *a*, on back of passage portion A, and exposing the printed matter on the stub portion B. Fig. 2 is the ticket folded in normal position for agent's use, showing face of the passage coupon A, and having the necessary pencil and stamp impressions thereon adapting it to valid passage on train.

I prefer to supply the tickets to agent, not bound, but folded as in Fig. 2, and merely held in a small pack by means, preferably, of a rubber band. It will be seen that the agent merely removes the uppermost ticket from the pack, inserts with indelible pencil or pen, on the passage coupon only, the name of station to which ticket is to be honored, the number of the mileage or scrip book presented by passenger, and the initials of the issuing railway; then, by one impression upon the face of the folded ticket of the agent's stamp, *b*, embracing the name of the railway, selling date and name of station from which the ticket is to be good for passage, the agent's work is completed and it only remains for him to separate the two coupons, handing one to the passenger and retaining the other for his record.

Having thus described my invention, what I claim as new and desire to secure by Letters Patent, is:—

A railway ticket comprising a single sheet having a weakened line for folding and separation and providing two sections, one section bearing printed matter on the obverse face constituting a passage portion and the other section bearing printed matter on its reverse face constituting a stub, the opposite faces of each section being provided with appropriately designated spaces for inserted matter so located as to be in register when the passage section is folded upon the stub section, the passage portion having on its unprinted face a transfer coating corresponding in position to the spaces for inserted matter.

JAMES D. GIBBS.
